CENTRIFUGAL SWITCH

Willis Z. West, Jr., and Morgan F. Gamble,
Winston-Salem, N. C.

Application February 26, 1946, Serial No. 650,352

9 Claims. (Cl. 200—80)

1

Our invention relates to centrifugal fluid operated switches.

An important object of the invention is to provide a switch of the above mentioned character, wherein terminals are electrically connected by a conducting liquid such as mercury, when the rotor is at rest or is moving slowly and breaks the electrical connection, when the speed of rotation of such rotor increases.

A further object of the invention is to provide a device of the above mentioned character, which is extremely simple in construction and is a completely assembled unit, which may be readily installed in place, without the necessity of making adjustments, requiring the services of a skilled attendant.

A further object of the invention is to provide a device of the above mentioned character, which will operate properly when mounted upon the armature shaft of a motor, regardless of the angular position that the device assumes upon the shaft.

A further object of the invention is to provide a device of the above mentioned character which may be installed upon a horizontal or vertical shaft.

Other objects and advantages of the invention will be apparent during the course of the following description.

In the accompanying drawings forming a part of this application and in which like numerals are employed to designate like parts throughout the same,

Figure 1 is a perspective view of a switch embodying my invention.

Figure 2 is an end elevation of the same.

Figure 3 is a central vertical longitudinal section through the device.

Figure 4 is a vertical section taken on line 4—4 of Figure 3.

Figure 5 is an exploded perspective view of the switch.

Figure 5a is a horizontal section through the tubular arm, and,

Figure 6 is a central vertical section through a modified form of switch.

In the drawings, where for the purpose of illustration are shown preferred embodiments of my invention, attention being called first to Figures 1 to 5 inclusive, the numeral 10 designates a horizontal sleeve or bushing, formed of insulating material, such as fiber, plastics, or the like. Rigidly mounted upon the insulating sleeve 10 are connecting or contact rings or elongated sleeves 11, formed of copper or the like. These

2

rings or elongated sleeves have a press fit upon the sleeve 10 and their outer ends preferably terminate flush with the outer ends of the sleeve 10. The rings or elongated sleeves 11 are preferably of the same length and their inner ends are spaced forming an annular passage 12. This annular passage leads into an annular groove 12', disposed at the longitudinal center of the sleeve 10. This groove or chamber 12' is formed in an annular housing or body portion 13, formed of insulating material, such as fiber, plastics or the like. The housing 13 has end openings 14, for receiving the inner ends of the rings or elongated sleeves 11, having a driving fit therein, so that the housing is rigidly secured to the rings or elongated sleeve 11 to rotate therewith and a liquid tight joint is effected. The housing 13 has a port 15, to be covered by a removable plug 16, and this port leads into the annular groove or chamber 12'. This chamber is preferably U-shaped in cross-section, with its large open side arranged next to the passage 12 and in free communication therewith. The groove 12' receives an electrical conducting liquid, such as mercury 18. This mercury is fed into the groove through the port 15. The elements 10, 11 and 13 are rigidly connected and rotate as a unit. The numeral 19 designates brush holders, which are slidably mounted upon the rings or elongated sleeves 11. Each brush holder comprises an annular hub 20, slidably receiving the ring or elongated sleeve 11, which is rotatable therein. Each hub has a radial tubular arm 21, having a bore 22, which is preferably square in cross-section for receiving a brush or carbon 23, which is also square in cross-section. This brush has a concave face 24, to properly contact with the ring 11. The brush 23 is forced inwardly by a spring 25, carrying a contact disc 26 at its outer end, connected with a wire 27, connected at its inner end to the brush 23. A terminal plug 28 screws into the cylindrical bore 29 of the arm 21 and contacts with the disc 26 and therefore has electrical connection with the brush. The terminal plug 28 carries the usual binding post 30. The annular hub 20 is provided opposite to the tubular arm with a radial arm 30, and these arms have openings, transversely arranged for receiving a screw 31. This screw is clamped to the arms by nuts 31'. A strap 32 is secured to the screw 31, as shown, and may be attached to a stationary part 33, for holding the connected brush holders against turning movement.

The operation of the device is as follows:
The sleeve 10 is suitably rigidly applied to the

horizontal armature shaft 33 of a motor and rotates therewith. This motor is of the split phase type, or may be of the capacitive type. The split phase type motor has a starting stator winding and a running stator winding. As is well known, in starting a motor of this type, current is first supplied to the starting and running stator windings, and when the motor speeds up current is cut off from the starting stator winding. The present switch is employed to supply current to the starting stator winding to start the motor and to cut the current off when the motor speeds up. When the motor is at rest, the mercury 18 is accumulated in the bottom of the annular groove 12' and has a sufficient level so that it contacts with the lower portions of the rings 11, thus closing the circuit between these rings and supplying current to starting stator winding. As the motor speeds up, the unit including the rings 11 has its speed of rotation correspondingly increased, and the mercury is thrown outwardly by centrifugal force and moves to the outer surface of the groove 12', forming a shallow ring of mercury, out of contact with the rings 11. The circuit is then broken between these rings.

Our device is an entirely self contained unit, as all parts are permanently assembled, when the sleeve 10 is applied to the armature shaft. The strap 32 is then secured to the stationary part 33', and the wires connected with the binding posts 30'. This is practically all the adjustments which need be made, and these do not require the service of a skilled electrician. It is immaterial what angular positions the brush holders have with respect to the rings 11. Since the contacts or brushes 23 are exteriorly of the housing 13, there is no tendency for the device to short circuit across the inner ends of the rings or elongated sleeves 11, due to carbon dust. Further, the contacts or brushes 23 are covered, and there is very little, if any, liability of flying sparks being produced, due to improper contact between the brushes and the rings, if improper contact should occur. By virtue of the tubular hubs 20 slidably engaging the rings 11, these rings are kept clean, for proper contact with the brushes 23, and the device is self cleaning. The device is extremely simple and formed of few parts, not liable to derangement.

We also contemplate providing a device for use upon a vertical armature shaft 33^a. This device is shown in Figure 6. The sleeve 10 is now mounted upon the vertical armature shaft 33^a, to rotate therewith. A housing 13' is provided, having an annular groove 35. This annular groove has inclined top and bottom walls 36 and 37, which lead into the annular space 12. The housing 13' is otherwise identical with the housing 13. All other parts of the device are identical with those shown and described in connection with the first form of the invention, except that the sleeve 10 and rings 11 are vertical and the housing 13' and brush holders 20 are horizontal.

When the vertical armature shaft 33^a is at rest, the mercury 38 gravitates to the bottom of the groove 35 and has a sufficient level to electrically connect the upper and lower rings 11. When the motor speeds up, the mercury is acted upon by centrifugal force and travels outwardly and upwardly, breaking contact with the lower ring 11 or both upper and lower rings 11. It is thus seen that this device may be employed to supply current to the starting stator winding, when the motor starts, and will cut off this current when the motor speeds up.

It is to be understood that the form of our invention herewith shown and described is to be taken as a preferred example of the same and that various changes in the shape, size, and arrangement of parts, may be resorted to, without departing from the spirit of our invention or the scope of the subjoined claims.

Having thus described our invention we claim:

1. A centrifugal switch comprising axially arranged opposed elongated metallic sleeves having their inner ends disposed near each other and spaced for providing a passage, means to connect the elongated sleeves and insulate the same, an insulating housing mounted upon the inner ends of the elongated rings and having a liquid tight connection therewith and covering the passage between the inner ends of the sleeves, said housing having a substantially annular recess in communication with said passage, the elongated sleeve extending axially and outwardly beyond the ends of the housing, mercury held within the annular recess, brush holders arranged outwardly of the housing adjacent to their ends and slidably mounted upon the outer portions of the sleeves, and brushes carried by the brush holders and engaging the sleeves.

2. A centrifugal switch comprising an insulating sleeve, elongated metallic contact sleeves mounted upon the insulating sleeve and having their inner ends arranged near each other and spaced to provide a substantially annular passage, an insulating housing mounted upon the inner ends of the elongated sleeves and covering the substantially annular passage and having a substantially annular recess in communication with such passage, the rings extending axially and outwardly beyond the ends of the housing, mercury held within the substantially annular recess, brush holders disposed exteriorly of the housing adjacent to its ends and having openings to rotatably receive the outer portions of the elongated sleeves, and brushes carried by the brush holders for engagement with portions of the elongated sleeves which are covered by the brush holders.

3. A centrifugal switch comprising an insulating sleeve, elongated metallic contact sleeves mounted upon the insulating sleeve having their inner ends arranged near each other and spaced to provide a substantially annular passage, an insulating housing mounted upon the inner ends of the elongated metallic sleeves and covering the substantially annular passage and having a substantially annular recess in communication with such passage, the outer portions of the elongated metallic sleeves extending axially and outwardly beyond the ends of the insulating housing, mercury held within the substantially annular recess, brush holders arranged exteriorly of the housing and adjacent to the ends of the housing and having hubs provided with recesses for rotatably receiving the outer portions of the elongated sleeves, tubular arms carried by the hubs and having bores which lead into the openings of the hubs, brushes mounted within the tubular arms to contact with the elongated sleeves, resilient means to move the brushes inwardly, and means connecting the hubs and serving to hold them in place upon the elongated sleeves.

4. A centrifugal switch comprising an insulating sleeve, elongated metallic contact sleeves mounted upon the insulating sleeve and having their inner ends arranged near each other and spaced to provide a substantially annular passage, an insulating housing mounted upon the in-

her ends of the elongated sleeves and covering the annular passage and having an annular recess in communication with such passage, brush holders arranged exteriorly of the housing adjacent to its ends and including hubs having openings to rotatably receive the outer portions of the elongated sleeves, said brush holders having radial openings which extend to the openings of the hubs, brushes mounted within the radial openings to contact with the elongated sleeves and covered by the hubs, resilient means to move the brushes inwardly, generally radial arms carried by the hubs, and means to connect the generally radial arms.

5. A centrifugal switch comprising an insulating sleeve, elongated metallic contact sleeves mounted upon the insulating sleeve and having their inner ends arranged in close relation and spaced to provide an annular passage, an insulating housing mounted upon the inner ends of the elongated sleeves and covering the passage and having an annular recess in communication with such passage, the elongated sleeves extending axially and outwardly beyond the housing, insulating brush holders disposed outwardly of the insulating housing adjacent to its ends and having openings to rotatably receive the outer portions of the elongated sleeves, the brush holders serving to clean the outer portions of the elongated sleeves, brushes mounted within the brush holders to contact with the elongated sleeves, extensions carried by the brush holders, a pin connecting the extensions, and a strap secured to the pin.

6. A centrifugal switch comprising an insulating sleeve adapted to be mounted upon a shaft for rotation therewith, elongated metallic contact sleeves mounted upon the insulating sleeve and having their inner ends arranged near each other and insulated from each other, an insulating housing mounted upon the inner ends of the contact sleeves to rotate therewith, the outer ends of the contact sleeves extending axially and outwardly beyond the ends of the insulating housing, centrifugally operated contact means mounted within the housing for co-action with the inner ends of the contact sleeves, brush holders having openings to rotatably receive the outer end portions of the contact sleeves and covering such outer portions and serving to clean such outer portions by contact therewith, and brushes carried by the brush holders to contact with the contact sleeves.

7. A centrifugal switch comprising a horizontal insulating sleeve to be mounted upon a rotatable shaft, elongated metallic contact sleeves mounted upon the insulating sleeve and having their inner ends arranged near each other and insulated from each other, a vertical insulating housing mounted upon the inner ends of the contact sleeves and having an annular recess, mercury

held within the annular recess, vertical brush holders having openings to rotatably receive outer ends portions of the contact sleeves which project outwardly beyond the vertical housing, brushes carried by the brush holders and engaging the contact sleeves, and means to hold the brush holders against turning movement.

8. A centrifugal switch comprising a vertical insulating sleeve to be rotated, elongated metallic contact sleeves mounted upon the insulating sleeve and having their inner ends insulated, a horizontal insulating housing mounted upon the inner ends of the insulating rings and having an annular recess which is vertically inclined outwardly in an upward direction, horizontal insulating brush holders arranged above and below the housing and having openings to rotatably receive the contact sleeves, mercury held within the annular recess, brushes carried by the brush holders, and means connecting the brush holders.

9. A centrifugal switch comprising an insulating sleeve to be rotated, elongated metallic contact sleeves mounted upon the insulating sleeve and having their inner ends arranged near and insulated from each other, an insulating housing mounted upon the inner ends of the contact sleeves for rotation therewith, the contact sleeves extending axially and outwardly beyond the housing, centrifugally operated contact means

30 mounted within the housing for co-action with the inner ends of the contact sleeves, brush holders having openings to rotatably receive the outer end portions of the contact sleeves and disposed adjacent to the opposite ends of the housing, the brush holders having generally radial openings leading to their contact sleeve receiving openings, brushes arranged within the generally radial openings, binding posts mounted upon the

40 brush holders, springs to move the brushes toward the contact sleeves, the binding posts and brushes being electrically connected, and means to prevent the brush holders moving axially from the insulating housing, the arrangement being such that the insulating housing covers the inner ends of the contact sleeves so that a short circuit cannot occur at such inner ends due to carbon dust and the brush holders clean the outer end portions of the contact sleeves by engagement therewith and enclose the brushes.
